SHAVING IMPLEMENT

Leo Axien, Altona-Elbe, Germany

Application July 18, 1934, Serial No. 735,896
In Germany November 6, 1933

1 Claim. (Cl. 30—85)

Shaving elements of conventional type have the disadvantage to constitute a system of rigidity. In such shaving elements, it has already been proposed to connect the blade holding member to the handle in a flexible manner, or to construct the handle so as to constitute wholly or partially a flexible member, but experience has shown that, owing to such a construction, shaving is unfavorably influenced. Indeed, it is well known that not all of the hands are equally fit for manipulating a shaving implement: numerous persons are hard-handed, and the hands of other persons show total absence of suppleness, or are extremely unskillful. It is, therefore, not astonishing that even in case of a sharpest and finest blade being used, it will be impossible to get a clean and velvet shave.

In accordance with the invention, the handle, which may have a flexible structure, and be connected to the blade holding member in any suitable manner, is made of rubber mass so that it possesses flexibility over the whole of its length and that it is susceptible of deformation in all directions. Such a handle is adapted to immediately conform to any pressure exerted by the manipulating hand, or by the fingers, and to conform to any position of the fingers. The blade holding member and the blade itself are, therefore, no longer influenced by the pressure of hand and fingers: on the contrary, the blade is susceptible of adapting itself yieldingly to the skin which needs no longer be tensioned. Thus, the skin is treated with utmost care, and unfit movements of the fingers cannot be transmitted to the blade.

The handle may be of tubular shape, this construction having the advantage to increase the capability of deformation of the handle. In this respect, it has already been proposed to provide safety razors with handles made of rubber, and with hollow spaces designed for the reception of shaving-paste: but it is a matter of fact that such handles do not at all allow of a secure manipulation of those razors. The construction in accordance with the invention also offers considerable advantages over handles which are constituted by a spiral spring, the reason being that a spiral spring is subjected to bending stress, but as there is no damping action, the spiral spring does not coil suddenly after each bending imparted, and does thus produce dangerous effects upon the razor blade. Whereas the present handle which over the whole of its length is constituted by rubber material, does when subjected to the same bending stress, softly and slowly return to

its initial position, by virtue of its great, inner damping action.

In order to more fully disclose the nature and characteristic features of my invention, I shall describe my improved shaving implement, illustrated in the accompanying drawing, in which

Fig. 1 is a side elevation, and

Fig. 2 a front elevation, said figures showing in dotted outlines the details of deformation of the resilient-flexible handle. It should be understood, however, that my invention is not limited to the particular structure illustrated, but is susceptible of various modifications.

The handle 5 of the present shaving implement is made of soft rubber and is in consequence capable of being bent and deformed in accordance with the varying pressure of the fingers, as shown in dotted outlines 5a in the drawing. In the plurality of cases, merely a slight bending of the handle will come into consideration, just as much as no strong resistance is being felt: the deformations shown in dotted outlines in the drawing, and traced rather exaggeratedly, should in practice scarcely occur. Persons, who suffer from finger's cramp, writer's cramp, and the like, will have the pressure of their fingers strongly decreased between thumb, forefinger, and middle finger.

Handles made of rubber material which is provided with metal insertions for stiffening purposes, have already become known. But those handles have the disadvantage not to be susceptible of bending and deformation in all directions, the reason being that the cross-section of the metal insertions does not permit of such a bending or deformation.

The surface of the present handle may in customary manner be fitted with grooves, or depressions, and projections 6 of any kind, preferably extending lengthwise of the handle for the purpose of facilitating a secure hold of said handle between the fingers but ineffective to retard flexibility of the handle. The cross-section of the handle may be circular, or square, or the like, or the handle may have an entirely flat shape, always with the end in view to provide a handle having sufficient resiliency.

The main object of the invention is to construct the handle of a shaving implement so as to be capable of adaptation to the hand and to the fingers, in such a manner that the material is susceptible of accommodating itself to the position of the fingers and of maintaining the material in its deformed shape temporarily or permanently, it being understood that changes may be

made in the details of construction, without departing from the spirit of the invention.

The great advantage of the invention consists, first, of the flexibility of the handle, the said 5 flexibility making shaving easier, thereby taking care of the skin of the face in a manner hitherto unknown, and secondly, of the deformability of the handle in all directions, the said deformability allowing a smooth and elastic shaving to persons who suffer from cramp in general and writer's cramp in particular, nervous disorders, and the like, and who exert strong pressure upon the handle.

My improved handle 6 may be connected to 15 the blade holding member 7 by means of the usual internal thread tap 8, or by any other suitable means, and the extremity of the handle may be provided with ornamental knobs 9 made of solid

material that constitute end abutments for the fingers of the hand during use of the razor.

What I claim is—

A safety razor of the type employing a double edged flexible blade and having a threaded stud 5 projecting therefrom, a flexible handle for said razor, said handle having a threaded socket for engaging said threaded stud and characterized by the handle being over the whole of its length made of a relatively soft rubber mass of tubular formation so that the said handle is over the whole of its length susceptible of bending and deformation in all directions uniformly, and the outer face of the handle being longitudinally grooved and ribbed to facilitate gripping thereof and to permit 10 longitudinal sliding movements of the user's hand.

LEO AXIEN.
